(57) **CLAIM**

The ornamental design for a swing spin set, as shown and described.

DESCRIPTION

FIG. 1 is a perspective view of a swing spin set showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, right, bottom perspective view thereof;

FIG. 9 is an enlarged detail view of area 9 shown in FIG. 1;

FIG. 10 is an enlarged detail view of area 10 shown in FIG. 2; and,

FIG. 11 is an enlarged detail view of area 11 shown in FIG. 8.

The evenly spaced broken lines in the drawings depict portions of the swing spin set that form no part of the claimed design. The dot-dash broken lines are for purpose of depicting the boundary lines of the enlarged views and form no part of the claimed design.

1 Claim, 11 Drawing Sheets
